(57) **CLAIM**

The ornamental design for a press fit door peephole cover, as shown and described.

DESCRIPTION

FIG. 1 is a right-side elevational view of a press fit door peephole cover embodying the ornamental design constituting my invention, the left-side elevational view being a mirror image of the right-side elevational view;

FIG. 2 is a perspective view of the cover illustrated in FIG. 1 showing a front face;

FIG. 3 is a bottom view of the cover illustrated in FIGS. 1-2, the top view being a mirror image of the bottom view; and, FIG. 4 is a perspective view of the cover showing a rear face of the cover illustrated in FIGS. 1-3.

The broken lines shown in FIG. 1 of a door and peephole represent environmental structure and form no part of the claimed design.
